United States Patent Office

Des. 208,672
Patented Sept. 19, 1967

208,672

CONTAINER FOR DRY PRODUCTS OR THE LIKE

Martin Schnur, West Orange, and Mel Appel, Livingston, N.J., assignors to American Can Company, New York, N.Y., a corporation of New Jersey

Filed Dec. 30, 1965, Ser. No. 375

Term of patent 14 years

(Cl. D58—2)

FIG. 2

FIG. 1

FIG. 3

We claim:

The ornamental design for a container for dry products or the like, as shown.
